UNITED STATES PATENT OFFICE

98,734

DESIGN FOR A DENTAL FLOSS MAGAZINE

Chester E. Orrison, Chicago, Ill., assignor of one-half to Joel E. Reed, Chicago, Ill.

Application November 16, 1935, Serial No. 59,609

Term of patent 14 years

To all whom it may concern:

Be it known that I, Chester E. Orrison, a citizen of the United States, residing at Chicago, in the county of Cook and State of Illinois, have invented a new, original, and ornamental Design for a Dental Floss Magazine, of which the following is specification, reference being had to the accompanying drawing, forming a part thereof.

Fig. 2 is a side view showing the side opposite that shown in Fig. 1.

Fig. 3 is an end view thereof.

I claim:

The ornamental design for a dental floss magazine as shown.

CHESTER E. ORRISON.
